UNITED STATES PATENT OFFICE

2,245,508

SANITARY LAMINATED PAD

George B. Travis, Washington, D. C.

Application November 22, 1937, Serial No. 175,992

1 Claim. (Cl. 154—46)

This invention concerns personal hygiene and aims to provide a sanitary and effective means for cleansing after defecation.

It is especially an object to provide such a means which is inexpensive and capable of manufacture in small size with ability to accommodate and discharge an ample quantity of cleansing liquid, and such a means as will not shred or disintegrate through the washing or cleansing motion, although the means will pass off in toilet bowls and disintegrate in the water upon standing therein, with equal facility with toilet paper so as to avoid danger of clogging or stoppage.

Another object is to provide a means of the present character which will aid in the prevention of rectal diseases and disorders caused by irritations and infections resulting from fecal matter lodging in minute crevices or fissures.

More specifically, the invention provides a layer or wad of cellulosic material for absorption, retention and subsequent discharge of cleansing liquid covered at least on the washing side with a material which is less readily disintegrable, as, for instance, a layer of absorbent cotton, the other side being covered by a layer of paper or the like overlapping a portion of the absorbent cotton, which paper is tougher and less rapidly disintegrable than the cellulosic material and absorbent cotton, giving body and strength to the assembly while it is being used and enabling the user to handle the assembly in a sanitary manner.

One more phase of the invention is to produce a novel unitary cabinet and normally closed liquid-dispensing means to contain a supply of the articles for individual removal and application against the liquid-dispensing means to receive a supply of the liquid.

The more specific objects and advantages will in part be pointed out and otherwise become apparent from a consideration of the description following taken in connection with accompanying drawing illustrating one embodiment, by way of example.

In said drawing,

Figure 1 is a perspective view of the personal hygiene article constructed in accordance with the invention;

Figure 2 is a side elevation of a modified form of such an article;

Figure 3 is a front elevation of a unitary container cabinet and liquid-dispensing means used with the article, with the cover removed to disclose details;

Figure 4 is a perspective view of such cabinet;

Figure 5 is a horizontal sectional view taken through the entire cabinet on the plane of line 5—5 of Figure 3;

Figure 6 is an inverted plan view of the cabinet; and,

Figure 7 is a longitudinal detail sectional view through the liquid-dispensing valve.

Referring specifically to the drawing wherein like reference characters designate like or corresponding parts, and first to the personal hygiene article or washer, the assembly is designated 10 and may be manufactured in any desired size, for instance, approximately two inches square and one-half of an inch thick. This article 10 has a wad or layer 11 of cellulosic material against which is disposed a layer 12 preferably of absorbent cotton although it may be of textile fabric or any equivalent. Wad or body 11 may be of that character designated as cellulosic tissue; a kind of paper of layer built type or free subdivided type; creped cellulose paper; loosely packed layers of cellulose sulphite fibers, or the like. Such layer 12 is adapted for cleansing contact with the body after defecation.

15 Said wad 11 and layer 12 are adapted to be saturated with a liquid and the body after defecation is cleansed directly with the layer 12 aided by the liquid. The layer 12 will not shred or disintegrate during the said washing and cleansing 20 action like the cellulosic material 11 will do and the danger of shreds or particles containing the liquid and/or fecal matter remaining on the body or being caught in the clothing is avoided. At the same time, the cellulosic material is employed because of its superior ability to absorb, hold and discharge a greater quantity of water per unit of size than the absorbent cotton, and thus to ultimately discharge the maximum quantity of liquid. While said wad 11 and layer 12 25 are usually saturated with water, any desired liquid may be employed and the water or other liquids may contain a disinfectant or other chemical, if desired, and this is to be understood whenever water is herein specifically referred to.

30 Against the other side of the wad 11, a layer or sheet 13 is provided being preferably of relatively tough paper so as to give body and strength to the assembly and to be impermeable to the water during the short time it remains in the hand. Thus, there is minimum danger of contact of the hand with the water and/or fecal matter.

35 To aid in gripping and holding the article 10 with maximum sanitation, said paper 13 has a flange or end portion 14 turned to overlap a portion of the absorbent cotton layer 12. Said 40

45

wad 11, layer 12 and paper 13 need not be attached to each other, as it is sufficient if they are merely in contact. The used articles 10 are dropped in toilet bowls like ordinary toilet paper, and are disintegrable by the water to avoid danger of clogging or stoppage.

As shown in Figure 2, a second layer of textile material 12^a may be employed, which is interposed between the wad 11 and paper sheet 13, which adds body to the assembly.

The said articles 10 may be packed, stacked, or arranged in any desired or convenient manner. For example, I provide a cabinet 15 having vertical partitions 17 to provide vertical side compartments 18 in which the articles 10 are superposed and retained by a bottom wall 20 and lateral flanges 19 on the sides of the cabinet and on the partitions 17. A removable liquid container 21, for instance, of glass, is located between the partitions 17, resting on wall 20 and retained behind vertical flanges 20^a on said wall 20. A reinforcing bar 22 extends across cabinet 15 at the top and is connected to the flanges 19. Container 21 has a normally closed discharge valve device 24 in its base, about which the wall 20 is cut away at 23 to permit insertion and removal.

Container 21 fits somewhat loosely in the cabinet and extends above bar 22. There is sufficient clearance between the parts to enable the container to be inserted by disposing the same behind bar 22 and above flanges 20^a and then permitting the container to lower behind flanges 20^a onto wall 20.

A cover section 25 fits over cabinet 15, and consists of a main wall 26 and an upper wall or flange 27. Wall 26 at its lower edge is hinged at 26^a to the forward edge of wall 20 to permit the cover section to be lowered and it is cut away at 23^a in continuation of space 23 for the same purpose. Such cover section 25 is held in closed position by a conventional latch at 27^a. Wall 26 has slots 28 and 29 therethrough so that the contents of the compartments 18 and the container 21 may be viewed.

Flanges 19 terminate above bottom wall 20 so that the washer articles 10 may be removed through slots 28 in wall 26, and the gripping of such articles is facilitated by notching the walls 20 as at 31.

Reverting to the valve device 24, it may be of any desired construction. For instance, it may be a tube or barrel 32 normally closed by a ball valve 33 contacting a gasket 34 supported by a flange 35 and urged to its seat by an expansive coil spring 36 bearing against a neck 37 surrounding the outlet opening 38 of the container. Said tube 32 is detachably screw threaded at 39 to said neck to permit removal of the valve device for inspection and repair and to enable refilling of the container through said opening 38. The ball 33 projects partly outside of the tube 32. One or more of the articles 10 may be used for each cleansing operation and any of such articles may be pressed momentarily against the ball 33 to open it to permit water or other liquid to flow onto the layer 12 and wad 11, following the removal of each article, the valve or ball 33 automatically closes or seats.

Various changes may be resorted to within the spirit and scope of the invention.

I claim as my invention:

A sanitary laminated pad for toilet purposes, comprising a layer of cellulosic wadding of the same compactness throughout and disintegrable in water, a layer of absorbent cotton of the same compactness throughout disposed over the aforementioned layer in water-absorbing contact therewith, and a backing layer of tough water-resistant paper approximately coextensive with the aforementioned layers having a portion extending in overlapping relationship at one end only over said layer of absorbent cotton, said overlapping portion covering only a narrow strip of the layer of absorbent cotton, all of said layers being readily separable.

GEORGE B. TRAVIS.
